UNITED STATES PATENT OFFICE.

WLADYSLAW RUDNICKI, OF WARSAW, RUSSIA.

SNOW-GUARD.

SPECIFICATION forming part of Letters Patent No. 361,783, dated April 26, 1887.

Application filed November 30, 1886. Serial No. 220,248. (No model.)

To all whom it may concern:

Be it known that I, WLADYSLAW RUDNICKI, a subject of the Emperor of Russia, residing at the city of Warsaw, in the Kingdom 5 of Poland, Empire of Russia, have invented certain new and useful Improvements in Snow-Guards, of which the following is a specification.

This invention relates to new and useful improvements in the guards placed adjacent and along railway-tracks at cuts, &c., for the prevention of accumulation of snow in said cuts, &c.

The invention consists in the construction 15 and arrangement of the guards, as will be fully described and set forth hereinafter.

In the accompanying drawings, Figure 1 is a diagrammatical view showing the effect of the wind. Fig. 2 is a cross-sectional view of 20 a cut and a snow-guard of the construction used heretofore. Fig. 3 is a sectional plan view of a part of my improved snow-guard. Fig. 4 is a cross-sectional view on the line $x-x$, Fig. 3. Fig. 5 is a cross-sectional view on the 25 line $y-y$, Fig. 3. Fig. 6 is a plan view of the snow-guard made of earth-work or stone. Fig. 7 is a cross-sectional view on the line $w-w$, Fig. 6. Fig. 8 is a sectional view on the line $v-v$, Fig. 6.

Similar letters of reference indicate corresponding parts.

Recent experiments and observations disclose the fact that all winds near the surface of the earth blow in a direction at an inclination to the surface, and thus give a serpentine or wavy movement to the layers of air directly above the surface, and that the snow raised from the surface of the earth by the wind is lifted quite a distance, and then gradually released and moved forward in a direction at an 35 inclination to the surface.

The snow-guards used heretofore usually consisted of upright fences or guards along the tracks, which have the effect of checking 45 the movement of the lower layers of air, so that the air beyond the said guard had no movement and dropped the snow which it held in suspension into the cuts, just where the depositing of such snow was to be prevented. Part of the snow that is dropped to the earth 50 is raised by the action of the moving air, and

mixes with the snow dropping from the clouds, and with the same is moved forward by the action of the wind. When the lifting power of the wind is decreased, the snow is dropped 55 and deposited until the quantity of the snow held in suspension is equal to the lifting power of the wind. The wind rebounding from the earth prevents the depositing or dropping of the snow, and as the power of the wind increases 60 the force of the rebounding wind also increases, and thus less snow is deposited.

If, for example, A B, Fig. 1, represent a certain distance on the surface of the earth, and the wind moves in the direction of the arrows 65 M N, the line $h' g' f' e' d' c' b' a'$ represents the currents of air next to the surface of the earth. The descending parts of the curve assist the depositing or separation of the snow from the air, whereas the ascending parts tend to prevent such separation. If a fence, wall, or other vertical obstruction, $m' n'$, is provided, the same 70 retards or destroys entirely the speed of the waves, and thus a certain quantity of snow is released and deposited directly behind said fence. Some distance behind said fence the waves of air have their full power, and less 75 snow is deposited than directly at the fence.

As shown in Fig. 2, B^2 represents a cut, and $m^2 n^2$ a fence or obstruction at the top of the 80 same, and $v^2 z^2$ a fence or obstruction some distance below the top of the cutting. $M^2 N^2$ represent the direction of the wind, and $M^3 N^3$ the direction of the wave. The wavy currents of air lift a certain quantity of snow, and arriving 85 at the fence or obstruction $m^2 n^2$ fully charged with snow, they are suddenly checked, and as there is no movement of the air beyond the fence the snow is dropped, as at A^2 , in the cut. It is thus evident that in all cases the ordinary 90 snow-guards are defective, and, in place of preventing the depositing of snow, assist the same.

So as not to destroy the lifting or carrying power of the lower strata of air, I make my 95 snow-guard in the form of truncated pyramids having triangular ground plan, and arrange a series of the same in line, whereby a series of funnel-shaped or V-shaped openings are formed, through which the powerful currents of air can pass, thus preventing a calm 100 behind the snow-guard—that is, the lifting

power of the air is not decreased by the guard. The inclined sides of the pyramids change the direction of the movement of some of the lower strata of air, so that the snow they hold is carried upward and over the tracks or cut. My improved guards cause the wind to lift and raise the snow from the track and carry it off with the snow held in suspense by the air.

My improved snow-guards are constructed in the following manner: Parallel with the line to be protected, the points $A^3 B^3 C^3 D^3 E^3 F^3$ are staked off, about in the manner shown in Fig. 3, the parts $A^3 B^3 C^3 D^3 E^3 F^3$ being the bases of equilateral triangles, the apices of which are at $w^3 q^3 t^3$. Taking the right-hand base triangle, Fig. 3, stakes are driven into the ground at $s^3 u^3$ at an angle of forty-five degrees to the interior of the structure, and at $h^3 i^3$ stakes are driven into the ground at an inclination of about sixty degrees to the interior of the structure. At w^3 and y^3 , I erect vertical posts, all the above-mentioned parts being suitably braced and united by transverse top beams, as shown in dotted lines in the right-hand triangle of Fig. 3. Planks are then nailed on the posts at E^3 , s^3 , u^3 , t^3 , and F^3 to form the side of the pyramid, and boards are nailed on the top to form an inclined roof, as shown in Fig. 5. Preferably the bottom plank does not extend to the surface of the earth, but is a short distance above the same to prevent rotting. If desired, the roof, which should be at an angle of about fifty degrees, may be omitted, as shown in Fig. 4; but I prefer the construction of the roof, as the same tends to deflect the current and throw the air upward, which greatly facilitates the carrying the snow over the cut or track. As shown in Figs. 6, 7, and 8, the snow-guards may also be constructed of earth-work. The line $A^6 Q^6$ is laid out in the manner previously set forth, to form the bases for three triangles. The guards are then made of earth-work or stone, as may be desired, the rear side having a greater or less bevel, as the nature of the material will allow, the front being beveled to about forty-five degrees to a certain height, and then beveled at about fifty degrees, as shown in Fig. 8, to form the top. The sides

of the truncated pyramids are preferably rounded, as indicated by the curved lines in Fig. 6. The bases of the rear bevels of the truncated pyramids are on the line $A^7 Q^7$, Fig. 6. In this case, also, funnel-shaped spaces are formed between the several truncated pyramids, which cause the wind to act in the manner as previously described.

Having thus described my invention, I claim as new and desire to secure by Letters Patent—

1. A snow-guard for railways, cuts, roads, &c., consisting of a series of truncated pyramids having triangular bases, the apices of the triangular bases being located farthest from the road, substantially as shown and described. 60

2. A snow-guard for railways, cuts, roads, &c., consisting of a series of truncated pyramids having triangular bases arranged in line along the road, said pyramids being separated a short distance from each other, substantially as shown and described. 65

3. A snow-guard for railways, cuts, roads, &c., consisting of a series of truncated pyramids having triangular bases, the apices of the triangles being farthest from the road, the two sides of the truncated pyramids not facing the road being beveled toward the center of the pyramid at an angle of about forty-five degrees, substantially as shown and described. 70 75

4. A snow-guard for railways, cuts, roads, &c., consisting of a series of truncated cones having triangular bases, the apices of the triangles being farthest from the road, the two sides of the truncated pyramids not facing the road being beveled toward the center of the pyramid at an angle of about forty-five degrees, and the truncated top of the pyramid being inclined in a direction from the apex toward the road upward at an inclination of about fifty degrees, substantially as shown and described. 80 85

In testimony whereof I have signed my name to this specification in the presence of two subscribing witnesses.

WLADYSLAW RUDNICKI.
